UNITED STATES PATENT OFFICE.

SIGMUND STERNAU AND CHARLES NELSON, OF NEW YORK, N. Y., ASSIGNEES TO S. STERNAU & COMPANY, OF BROOKLYN, NEW YORK, A COPARTNERSHIP.

DESIGN FOR A CHAFING-DISH AND STAND.

No. 39,885.

Specification for Design.

Patented March 16, 1909.

Application filed December 22, 1908. Serial No. 468,874. Term of patent 7 years.

To all whom it may concern:

Be it known that we, SIGMUND STERNAU, a citizen of the United States, and a resident of the borough of Manhattan, city, county, and State of New York, and CHARLES NELSON, a subject of the King of Sweden, and a resident of the borough of Brooklyn, county of Kings, city and State of New York, have invented a new, original, and ornamental Design for a Chafing-Dish and Stand, of which the following is a specification, reference being had to the accompanying drawing, forming part hereof, which shows a perspective view of the design.

The design comprises a dish, having a handle of substantially cylindrical shape, increasing in diameter toward the free end, a hot water pan having a ring-like exterior with oppositely opposed cylindrical shaped han-

dles supported upon curved brackets, a stand having legs of ogee curve, such legs having enlarged feet, reduced middle portions and enlarged upper portions, the reduction and enlargement being upon curved lines and the legs being joined together by curved portions, the rim of the legs raised, such raised rim of adjacent legs meeting in scroll work and a lamp support of circular shape connected to the legs by curved brackets.

We claim:

The ornamental design for chafing dish and stand, as shown and described.

SIGMUND STERNAU.
CHARLES NELSON.
